(57) CLAIM

We claim the ornamental design for a glove for a prosthetic arm, as shown and described.

DESCRIPTION

FIG. 1 is a perspective view of the glove for a prosthetic arm of the present design;

FIG. 2 is a front plan view of the present design, a corresponding rear plan view being a mirror image thereof;

FIG. 3 is right side view of the present design;

FIG. 4 is a left side view of the present design;

FIG. 5 is a top elevational view of the present design; and, FIG. 6 is a bottom elevational view of the present design. The broken lines shown on the glove are understood to represent stitching.
